(57) **CLAIM**

The ornamental design for the bearing for umbilicus of a fluid processing system, as shown and described.

DESCRIPTION

FIG. 1 is a front, left perspective view of a bearing for umbilicus of a fluid processing system;

FIG. 2 is a front, right perspective view of the bearing of FIG. 1;

FIG. 3 is a front view of the bearing of FIG. 1;

FIG. 4 is a cross-sectional view of the bearing along line 4-4 of FIG. 3;

FIG. 5 is a cross-sectional view of the bearing along line 5-5 of FIG. 3;

FIG. 6 is a top view of the bearing of FIG. 1 ;

FIG. 7 is a bottom view of the bearing of FIG. 1; and,

FIG. 8 is a rear view of the bearing of FIG. 1.

The features shown in broken lines depict environmental structure only and form no part of the claimed design. The broken lines which define the bounds of the claimed design form no part thereof.
